Inventor:

UNITED STATES PATENT OFFICE.

HERVEY D. MELENDY, OF NASHUA, NEW HAMPSHIRE.

SPOOL.

SPECIFICATION forming part of Letters Patent No. 408,732, dated August 13, 1889.

Application filed June 13, 1888. Serial No. 277,002. (No model.)

To all whom it may concern:

Be it known that I, HERVEY D. MELENDY, a citizen of the United States, residing at Nashua, county of Hillsborough, State of New Hampshire, have invented a new and useful Improvement in Spools, of which the following is a specification.

My invention relates to improvements in spools which have their heads and cylinders made of separate pieces of wood and then fastened together, but more particularly to such as are subject to great longitudinal strain and the heads of which are liable to pull off, such as are used for the winding of wire, where the tension is relied upon to straighten the wire, and for winding strong linen, cotton, or silk yarns or threads.

Heretofore much trouble has been experienced in making strong connections between the heads and barrels or cylinders, and various devices have been in use. The common method of fastening is by means of a thread cut on the ends of the cylinders which engages a corresponding thread cut in the hole in the head when the head is screwed onto the cylinder. Heads fastened in this manner come off from "stripping" of the thread. Another method is to make a taper or flaring hole through the head, and after placing the head on the cylinder expand the end of the cylinder by driving a taper plug into a hole in the center of the cylinder. Both this method and that of screwing on are quite liable to split the head, particularly if the head is of a single piece of wood cut either with or across the grain. Another method is to use a head with a tapering or flaring hole, a straight cylinder, and filling the open space with an annular wedge driven between the cylinder and head. This method is faulty in that the head easily comes off when the glue from any cause gives way. Still another method is to cut an annular groove in the head, the groove being the widest at the bottom, into which groove the end of cylinder is driven, first having an annular groove cut in its end, and into which an annular wedge has been lightly inserted in such manner that before the end of the cylinder reaches the bottom of groove in the head the annular wedge comes in contact with the bottom

and is forced up into the groove in the cylinder, thus expanding the end of the cylinder inside the hole in the head and making a "dovetailed" joint. This fastening is not as strong as mine, as it engages only a portion of the thickness of the head and is objectionable, as it causes a break in the inside bore of the spool where the wood of the head and cylinder should come together, thus making the bearing of the spool upon the spindle irregular and uneven, causing dirt to attach itself to the inside of the spool.

In the accompanying drawings, Figure 1 is an elevation of the spool. Fig. 2 is an end view of the same. Fig. 3 is a view of a section cut through the center of the spool, showing the different parts ready to be put together. Fig. 4 is a view of the end of the spool with a section cut away to show the connection of the head with the cylinder in the finished spool.

Similar letters refer to similar parts in the different views.

A is the head.

75

B is the hole in head.

C is the cylinder.

D is the annular groove in end of cylinder.

E is the annular wedge.

F is the spindle-bearing.

80

The heads may be of one or more pieces, with the grain of the wood running in line with the cylinder or at right angles to it.

I first bore a hole X through the head A, which hole is then made tapering the whole or a part of its length, as shown in Fig. 3, B. The end of cylinder C is turned to the same diameter as the smallest part of hole in head and in its end an annular groove of suitable depth is made, as shown in Fig. 3. The head is then crowded onto the cylinder, as shown in Fig. 3. Then the annular wedge E is forced into the annular groove D in the end of the cylinder C, expanding the outer shell of the end of the cylinder until it fills the space in the head, as shown in Fig. 4, making a so-called "dovetail" fastening. Glue can be used in the several constructions, if desired, but it is not absolutely necessary. This construction leaves the spindle-bearing F continuous and free from breaks or joints, and it will be seen that the heads cannot be pulled off by longi-

litudinal strain until the fiber of the end of cylinder is pulled apart, and in case the spool is used for wet yarn the head cannot come off even if the glue is all soaked away without first being split apart.

Having thus described my invention, what I desire to claim, and secure by Letters Patent, is—

1. The combination, with the cylinder having an annular groove in its end, of the head having a tapering hole therethrough, and the annular wedge entering the groove in the cyl-

inder end and expanding the cylinder end to fill the hole in the head, substantially as described.

2. The combination of the head A, having the tapering hole B, the cylinder C, having the annular groove D, and the annular wedge E, substantially as and for purposes described.

HERVEY D. MELENDY.
